Primary Examiner — Kelley Donnelly(74) *Attorney, Agent, or Firm* — Vidas, Arrett & Steinkraus, P.A.(57) **CLAIM**

The ornamental design for a keyboard stand, as shown and described.

DESCRIPTION

FIG. 1 is a perspective view of a keyboard stand showing the new design;

FIG. 2 is a perspective view thereof;

FIG. 3 is a bottom view of the keyboard stand of FIG. 1.

FIG. 4 is a top view of the keyboard stand of FIG. 1.

FIG. 5 is a front elevation view of the keyboard stand of FIG. 1.

FIG. 6 is a rear elevation view of the keyboard stand of FIG. 1; and,

FIG. 7 is a side elevation view thereof.

The broken lines showing a keyboard and wrist support in FIGS. 1, 2, and 7 are for the purposes of illustrating the environment of the article only and form no part of the claimed design.
